US00D903657S

(12) **United States Design Patent** (10) **Patent No.:** **US D903,657 S**
(45) **Date of Patent:** **** Dec. 1, 2020**

(54) **PERSONAL COMPUTER**

(71) Applicant: **Michael Ross Catania**, Laurel Springs, NJ (US)

(72) Inventor: **Michael Ross Catania**, Laurel Springs, NJ (US)

(73) Assignee: **Michael R Catania**, Laurel Springs, NJ (US)

(**) Term: **15 Years**

(21) Appl. No.: **29/670,930**

(22) Filed: **Nov. 20, 2018**

(51) LOC (12) Cl. **14-02**

(52) U.S. Cl.

USPC **D14/336**

(58) **Field of Classification Search**

USPC D14/336, 337, 341, 375, 376, 377, 127, D14/128, 129, 371, 372, 373, 374, 126

CPC G06F 1/1601; G06F 1/1605; G06F 1/162

See application file for complete search history.
